TYPEWRITER KEY LOCKING ATTACHMENT

Martha F. Cooke, Chicago, Ill.

Application August 14, 1939, Serial No. 290,120

6 Claims. (Cl. 197—17)

The invention relates to improvements in typewriter key locking attachments and more particularly to a novel attachment of this type especially suited for use on a power actuated typewriter.

One main object of the invention is to provide a novel typewriter attachment for automatically locking the key-levers against movement when the carriage reaches a selected limit position, and which is of such character as to insure effectual and accurate operation without danger of inadvertent locking when the carriage is short of its limit position, despite vibration incident to the operation of a heavy power driven typewriter.

A more specific object is to provide an attachment of the character indicated embodying a normally engaged key-lever lock having an electromagnetic lock-releasing mechanism together with a novel switch arrangement adapted to de-energize the lock-releasing mechanism, when the carriage reaches its limit position, so as to permit the lock to lock the key-levers, and also adapted to reenergize the lock-releasing mechanism in response to the release of a mechanical stop mechanism which normally serves to stop the carriage in its limit position.

Another object is to provide an attachment of the character indicated which may be easily and cheaply applied to completed typewriters already in use or alternatively incorporated in the machines in the course of their manufacture.

Further objects and advantages of the invention will become apparent as the following description proceeds, taken in connection with the accompanying drawing in which:

Figure 1 is a partial transverse sectional view of a typewriter, embodying the invention, with the electric circuits shown schematically.

Fig. 2 is a rear elevation of the carriage stop mechanism.

Fig. 3 is a fragmentary detail plan view of the limit switch and a portion of its actuating mechanism included in the machine of Fig. 1.

Fig. 4 is a fragmentary vertical sectional view along the line 4—4 of Fig. 1.

While typewriter attachments embodying the present invention are susceptible of various modifications and alternative constructions, I have shown in the drawing and will herein describe in detail the preferred embodiment. It is to be understood that I do not intend thereby to limit the invention by such disclosure, but aim to cover all modifications and alternative constructions

falling within the spirit and scope of the invention as expressed in the appended claims.

In its instant embodiment, the invention has been shown as applied to a so-called motor driven or power actuated typewriter (Fig. 1). To avoid unnecessary elaboration and confusion of parts only the novel attachment herein contemplated and the typewriter parts cooperating directly with it have been shown. The remainder of the machine is of well known construction and may, for example, embody a power actuating mechanism like that shown in R. G. Thompson Patent No. 1,777,055 issued September 30, 1930. For present purposes it is sufficient to note that the power actuating mechanism embodies an electric driving motor 10 which must be energized to render the machine operative. Upon depressing one or more of the key-levers 11 a suitable mechanism, driven by the motor 10, is released in a well known manner to cause the usual corresponding type bar (not shown) to place its imprint on a sheet of paper inserted about the roller or platen 12 on a carriage 14.

In accordance with the present invention, a novel attachment has been provided for automatically locking the key-levers 11 against movement whenever the carriage 14 reaches its limit or margin-stop position. Furthermore, the arrangement is such that the key-levers are automatically locked in the event of power failure of the motor 10 and are automatically released whenever the carriage 14 is freed from its mechanical stop, by the usual margin release key, for movement beyond its limit or margin-stop position.

Before proceeding with a description of the attachment noted, the parts of the typewriter cooperating directly with it will first be identified. The carriage 14 is of conventional form (Fig. 1) being mounted for endwise movement at the rear of the machine frame 15 on roller guides 16. On the rear of the carriage 14 is fixed a longitudinally extending and notched stop bar 17 (see also Fig. 2) which forms part of a conventional mechanical stop mechanism for stopping the carriage when it reaches a predetermined limit or margin-stop position. Adjustable along this stop bar 17 is a margin stop 18, engaged with selected teeth on the stop bar to determine the limit of travel for the carriage 14. Cooperating with the stop 18 is a stop member or lever 19 presenting at its left hand end a lug 19a (Fig. 1) located in the path of a complementary projection 18a on the stop 18 and engageable with it. Upon engagement of the pro-

jections 18^a and 19^a further travel of the carriage 14 is positively arrested.

The stop member 19 comprises an elongated sheet metal lever having an elongated slot 20 fashioned in its central portion. A pin 21 extends through this slot 20 and pivotally supports the lever 19 for limited swinging movement in a vertical plane. The pivotal supporting pin 20 extends between and is fixed to the 10 jaws of a bifurcated sheet metal supporting member 22 which is fixed on the stationary machine frame 15. The stop lever 19 is yieldably urged to the left (as viewed in Fig. 2) by contractile spring 23 anchored at its opposite ends to the supporting member 22 and to a depending lug 24 on the right hand end of the lever 19. In this way the stop lever 19 is supported for yielding bodily movement in an endwise direction and is normally biased by the spring 23 to the left hand 20 extremity of its path of endwise movement. It will be appreciated that when the stop 18 strikes the lug 19^a on the lever 19, the latter will be shifted endwise a short distance determined by the length of the slot 20. This endwise movement of the stop member 19, incident to engagement of it by the margin stop 18, is utilized in controlling the key-lever locking mechanism, as will hereinafter appear.

The key levers 11 are of conventional form and 30 are located in the usual manner at the forward or key board portion of the typewriter. The forward ends of these key-levers are received in guide slots 25 (Fig. 1) fashioned in a sheet metal channel 26. It will be noted that the downward 35 motion of the key-levers 11 when they are struck by the operator, is quite small as is usually the case in motor driven typewriters. Since only a small amount of key lever motion is required in the machine, it will be appreciated that the difficulties of providing an effectual locking mechanism are enhanced.

The main driving motor 10 has been shown simply diagrammatically. It may be energized from any suitable source of electric current to 45 which the supply lines L₁—L₂ are connected, such, for example, as an ordinary electric light circuit. Connections from the motor to the supply lines are completed through conductors 27, 28 in one of which is interposed a manually operable "on-off" switch shown in the form of a tumbler switch 29 mounted at some convenient point on the machine. When the switch is closed the supply line L₁ is connected by it to the motor conductor 27 while the other supply 55 line L₂ is permanently connected to the conductor 28.

Turning now to the key locking attachment herein shown, it will be seen, upon reference to Fig. 1 that it includes a locking blade or bar 30. 60 This blade is generally rectangular in form, being preferably fashioned as a sheet metal stamping, and is pivoted at its lower edge on a horizontal pin 31 to swing in a counterclockwise direction from its key-lever engaging position shown to a 65 released position in which it is tilted downward sufficiently to clear the lower edges of the key-levers. This locking blade is normally biased into locking position by a contractile spring 32 anchored at its opposite ends respectively to the locking blade and to the machine frame 15. When the locking blade 30 is in its locked position it presses the key-levers 11 firmly upward against the upper ends of the guide slots 25 in the channel 26 and thus effectually prevents depression of the keys by the operator.

Release of the locking blade 30 is accomplished by the energization of a solenoid 33 (Fig. 1). Axially movable within this solenoid is a cooperating armature 34, which is connected through a yieldable spring 35 with an integral arm 36 5 projecting from the locking blade 30 at substantially right angles with respect to the latter. The spring 35 is interposed in the system so that upon energization of the solenoid the armature 34 will be drawn almost instantly within the confines of 10 the solenoid and increase its inductive reactance, to prevent the solenoid from being burned out, even though the force thus stored up in the spring 35 by stretching the latter requires a 15 slightly longer interval of time to pull the locking blade free of the frictionally engaged key-levers 11.

Such an electromagnetically released locking mechanism has a number of advantages as compared to a purely mechanical locking system. 20 First, it is easier to apply to an existing machine. Second, the necessary controls for actuating the locking mechanism are very materially simplified. Third, strong and positive actuation 25 of the locking mechanism is insured and danger of inadvertent movement to locked position, due to vibration of the machine incident to its use, is obviated. Fourth, the locking mechanism can be easily interlocked by electrical circuits with 30 the main driving motor so as to insure automatic locking of the key board in the event of power failure for the motor.

By connecting the solenoid 33 in parallel with the motor 10 (Fig. 1) the interlocking of the motor and key-lever locking mechanism for the purpose noted above is accomplished. In the particular arrangement shown, one terminal of the solenoid 33 is connected to a corresponding terminal of the motor 10 through a conductor 37, while the other terminals are connected through 40 a conductor 38. A suitable dropping resistor 39 is inserted in the conductor 37 in the event that the solenoid 33 is wound for a lower voltage than the rated voltage of the motor. With the connection shown it will be seen that the solenoid 33 45 is connected inside the switch 29 so that this switch serves to energize and deenergize simultaneously both the solenoid and motor.

In order to release the locking blade 30 for movement to its locking position when the carriage 14 reaches its limit position, a control switch, designated generally by the numeral 40 (Figs. 1 and 3) is arranged to open-circuit the solenoid 33 in response to the endwise displacement of the stop member 19 incident to its being 55 struck by the stop 18. The switch 40 is a so-called micro-switch and includes a movable contact 41 normally urged to closed position with respect to a fixed contact 42 and moved to open position by the displacement of an actuating pin 60 43. This switch is interposed in series with the solenoid 33 in the latter's supply conductor 38 so that upon opening of the switch the solenoid is deenergized. A generally L-shaped bracket 44, fixed on the right hand end of the stop member 19 (Fig. 2) is positioned to engage the switch actuating pin 43 to open the switch when the member 19 is thrust endwise by the stop 18. It will thus be seen that the solenoid 33 is deenergized, and hence the spring 32 permitted to pull 70 the locking blade 30 upward into locking position, simultaneously with the stoppage of carriage motion by the mechanical carriage stop mechanism including parts 18 and 19.

To release the carriage 14 for movement be- 75

yond its limit position as, for example, to finish a word which the operator is typing, the usual margin release key 45 (Fig. 1) is provided. This key has a long stem 46 mounted for endwise movement and engageable at its inner end with a bell crank 47 pivoted on the frame at 48. The opposite end of the bell crank is pivotally connected at 49 with a lever 50 having a hook shaped upper end and inserted in a generally rectangular opening 51 (Fig. 2) in the right hand end of the stop member 19. A link 53 and a contractile spring 52 (Fig. 1) anchored to the lever 50 and to the frame 15, serve to hold the lever 50 in generally upright position during its vertical movement incident to oscillation of the bell crank 47. The opening 51 is of sufficient length that the nose of the bell crank will not interfere with the endwise movement of the lever 19. When the margin release key 45 is depressed the bell crank 47 is oscillated in a clockwise direction (as viewed in Fig. 1) thus moving the lever 50 upwardly and thereby swinging the stop member 19 in a counterclockwise direction (as viewed in Fig. 2). Such movement of the stop member disengages its lug 19a from the complementary lug 18a on the stop 18 so that the carriage movement can be continued as desired. At the same time the bracket 44 on the opposite end of the stop member 19 is disengaged from the switch actuating pin 43 so that the switch 40 is permitted to reclose, thereby reenergizing the solenoid 33 and unlocking the key-levers 11.

The operation of the typewriter shown will in general be clear from the foregoing. In brief, to condition the machine for use the operator closes the "on-off" switch 29, thereby connecting the motor 10 and solenoid 33 to the supply lines L₁—L₂. The resultant energization of the solenoid 33 causes it to draw down its armature 34, thereby swinging the locking blade 30 counterclockwise (Fig. 1) into unlocked position. Having thus freed the key-levers 11 for use the operator proceeds to type a line in the usual manner.

At the end of the line of typing the stop 18 engages the stop lever 19 and thus positively and mechanically stops the carriage 14 in its predetermined limit or margin-stop position. At the same time the resultant endwise shift of the lever 19 opens the switch 40. This deenergizes the solenoid 33 so that the spring 32 pulls the blade 30 back into locking position. By virtue of this automatic locking of the key-levers 11 the possibility is precluded of depressing a number of keys after the carriage is stopped and thus ruining the sheet by superimposing a number of characters at the end of the line.

Upon returning the carriage 14 to its starting position the lever 19 is freed by the stop 18 and is returned to its left hand position (Fig. 2) by the spring 23. Accordingly, the switch 40 is permitted to reclose and the solenoid 33 reenergized to unlock the key-levers 11 automatically for the next line of typing. Similarly, if the operator wishes to finish out a word at the end of the line the margin release key 45 (Fig. 1) is depressed. This swings the lever 19 counterclockwise (Fig. 2) freeing it from the stop 18 and also from the switch actuating pin 43. In this way the releasing solenoid 33 is reenergized and the key-levers 11 unlocked.

In the event of a power failure on supply lines L₁—L₂ the motor 10 is, of course, stopped, and in the present machine the solenoid 33 is deenergized as well. Consequently, the key-levers 11

are locked at once so that the operator cannot inadvertently depress a number of keys after the motor stops. In this way the piling up of a number of letters at one point on the line of typing, when the motor stops, is effectually prevented. 5

The application of the herein disclosed attachment to an existing machine is a simple matter. The switch 40 can be mounted on the rear of the frame 15 in an easily accessible position and a suitable bracket 44 fixed to the existing lever 19 to actuate the switch. Similarly, the solenoid 33 and locking mechanism can be mounted in the available space beneath the key-levers and the solenoid easily wired into the motor circuit. 10 If the attachment is to be built into a machine during its manufacture it is manifest that its inclusion is a simple matter and requires but a few inexpensive parts. 15

I claim as my invention: 20

1. In a typewriter, the combination of a power-driven actuating mechanism including an electric motor, a plurality of key-levers for controlling said mechanism, a releasable locking mechanism movable into and out of locking position for locking said key-levers against movement when in locked position, means normally urging said locking mechanism into locking position, means including an energizable electromagnet for releasing said locking mechanism in response to energization of the electromagnet, a carriage, mechanical stop means for arresting said carriage in a predetermined limit position, means including a switch for deenergizing said electromagnet to permit said locking mechanism to lock said key-levers, means for actuating said switch in response to engagement of said stop means, and means for energizing said motor and said electromagnet in parallel from a common electric circuit, whereby a power failure resulting in deenergization of said motor will also deenergize said electromagnet to permit said locking mechanism to lock said key-levers. 30

2. In a typewriter, the combination of a plurality of key-levers, a carriage having a margin stop thereon, movable means for releasably locking said key-levers, means for releasably maintaining said locking means in locking position, means including an electromagnet having an energizing circuit for releasing said locking means, 45 a stop member located in the path of said margin stop and disposed for yielding bodily movement, and a switch interposed in said electromagnet circuit and having an actuating member projecting into position to be engaged and moved 50 into switch-opening position by said stop member upon displacement of the latter by said margin stop. 55

3. In a typewriter, the combination of a plurality of key-levers, a locking member movable 60 into and out of locking engagement with said key-levers, means normally biasing said locking member into locking engagement with said key-levers, means including an electromagnet for moving said locking member to released position, 65 said electromagnet having an energizing circuit with a switch interposed in it, a carriage, and means for not only stopping said carriage in a predetermined position but for also substantially simultaneously opening said switch to deenergize 70 said electromagnet, and thereby permit said locking member to return to its normal key locking position. 75

4. In a typewriter, the combination of a traversable carriage, means including a pair of en-

- gageable stop members for positively arresting said carriage in a predetermined limit position, a plurality of key-levers, means for alternatively locking and unlocking said key-levers and having an electric control circuit, means including a switch interposed in said control circuit for conditioning said locking means to lock said key-levers, and means for actuating said switch in response to engagement of said stop members.
10. '5. In a typewriter, the combination of a plurality of key-levers, a carriage having a margin stop thereon, means for releasably locking said key-levers, means yieldably urging said locking means into locking position, means including an electromagnet having an energizing circuit for releasing said locking means, a stop member located in the path of said margin stop and disposed for yielding bodily movement, a switch interposed in said electromagnet circuit and having an actuating member projecting into position to be engaged and moved into switch-opening position by said stop member upon displacement of the latter by said margin stop, and means including a margin release key for substantially simultaneously shifting said stop member out of engagement with both said margin stop and said switch actuating member.
20. '6. In a typewriter, the combination of a sta-

tionary frame structure, a plurality of key-levers located on the front portion of said structure, a carriage traversable endwise along the rear portion of said structure, an elongated horizontally disposed stop lever located at the rear 5 of said structure and extending along the path of said carriage, pivot means at the central portion of said lever supporting it for pivotal movement in a vertical plane and for yielding bodily endwise movement, a margin stop adjustably 10 mounted on said carriage and engageable with one end portion of said lever to arrest carriage movement, means movable into and out of locking position for locking said key-levers, means yieldably urging said locking means into locking position, means including a switch for effecting release of said locking means upon closure of said switch, said switch having an actuating member disposed at the end of said lever opposite said one end and arranged to be moved 15 by said lever for opening of the switch upon the bodily endwise movement of said lever by engagement thereof by said margin stop, and means including a margin release key for swinging said lever about its pivot to disengage its respective 20 end portions from said margin stop and said switch actuating member.

MARTHA F. COOKE.
